UNITED STATES PATENT OFFICE.

CHARLES H. THURBER, OF EAST ORANGE, NEW JERSEY, ASSIGNOR TO THE
WIEBUSCH & HILGER, LIMITED, OF NEW YORK, N. Y.

DESIGN FOR A RAZOR-HANDLE.

SPECIFICATION forming part of Design No. 24,661, dated September 10, 1895.

Application filed August 6, 1895. Serial No. 558,427. Term of patent 7 years.

To all whom it may concern:

Be it known that I, CHARLES H. THURBER, a citizen of the United States, residing at East Orange, in the county of Essex and State of New Jersey, have invented and produced a new and original Design for Razor-Handles and the Like, (Case D,) of which the following is a specification.

This invention relates to a design for a razor-handle, as shown in the accompanying illustrations, wherein—

Figure 1 is a side elevation, and Fig. 2 an edge view.

The essential feature of my design resides in the surface ornamentation of the handle.

The general configuration of the handle is curved, and the exterior surface 1 is provided with a scale-like ornamentation 2, arranged

reversely from the center of such ornamentation, at which is on one side a scroll-like figure 3 and a fanciful figure 4 on the other side. The boundary of the scale-like figures at each end is defined at the top by an ornamental furcated figure 5, one side of which connects with the scroll-like figure 3 and at the bottom by a like figure 6, between the forks of which are a series of graduated ball-like figures 7 8.

I claim—

The design for handles for razors and the like, substantially as herein shown and described.

CHARLES H. THURBER.
